(57) **CLAIM**

The ornamental design for a portable data collector, as shown and described.

DESCRIPTION

FIG. 1 is a top, front and left side perspective view of a portable data collector showing my new design;

FIG. 2 is a top, rear and right side perspective view thereof;

FIG. 3 is a bottom, front and left side perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof; and,

FIG. 9 is a bottom plan view thereof.

The broken lines of FIG. 2, FIG. 5, and FIG. 8 illustrate portions of the portable data collector which form no part of the claimed design.
